Atty:

UNITED STATES PATENT OFFICE.

ARTHUR H. TROTTER, OF SYRACUSE, NEW YORK.

AUTOMATIC SPRINKLER HEAD.

Application filed April 22, 1924. Serial No. 708,285. Renewed June 22, 1926.

This invention relates to sprinkler heads, having a stem 5 extending through a guide opening 6 formed in a transverse web 7 connecting the side arms of the frame or body 1. After the fire has been extinguished and hence undue water damage is prevented.

The invention consists in the novel features and in the combinations and constructions hereinafter set forth and claimed.

In describing this invention reference is had to the accompanying drawings in which like characters designate corresponding parts in all the views.

Figure 1 is an elevation of one form of this sprinkler head.

Figure 2 is an elevation partly in section taken at a right angle to Fig. 1.

Figure 3 is a plan view of the thermostatic element.

Figure 4 is an elevation of the thermostatic element partly in section and parts being removed.

As is well known to those skilled in the art, the fusible elements of sprinkler heads can be melted by a comparatively insignificant fire and before the water can be turned off considerable more damage is done by the water than by the fire. The object of my invention is the production of a simple thermostatic element which is sure in its operation, and which is readily applied to, or self contained with the sprinkler heads themselves.

This sprinkler head comprises generally a body or open frame having a nipple at one end for attachment to the sprinkler pipe system, a valve having a head normally closing said nipple, a fusible element interposed between the valve and the body, and a thermostatic element self contained with the body and the valve and arranged to act on the valve to close the valve under low temperature conditions, after the fusible element has been melted by high temperature or fire conditions, and to close the valve under such low temperature conditions, and permit it to be opened again by the water pressure in case the fire again starts.

1 designates the body of the sprinkler head, which is shown as a frame formed of two opposite bow-shaped arms, and an attaching nipple 2 at one end, the nipple having a passage therethrough, and usually having a seat 3, at its inner end. 4 is the valve head normally engaged with the seat 3, and

8 is a fusible element usually interposed between the upper end of the body and the end of the stem, the body being usually provided with an adjusting screw head threading into the end remote from the nipple 2, and against which one end of the nipple 8 thrusts.

The thermostatic means is arranged to act directly upon the valve stem and as here shown comprises bow-shaped strips 10 and 11, of thermostatic material, the strips being bowed oppositely relatively to each other and having passages 12 midway between their ends through which the valve stem 5 extends. One of the strips as 10 thrusts at its central portion against the web 7 and the other strip 11 thrusting at its central portion against an adjustable shoulder as a nut or nuts 13 on the stem.

These thermostatic strips are of such a metal that they are normally flat and are bowed or tensioned when placed in position so as to push against the shoulder 13, in a direction tending to hold the valve stem seated, and acting under the influence of heat to flatten, and hence relieve the pressure on the shoulder or nut 13, so that the valve can open when the fusible element 8 is melted.

The strips 10 and 11 are enclosed in a suitable holder or container 14 which is here illustrated as rectangular in form, and folded from a strip of metal in the general form of a box open at its top and bottom and the end of the strips 10 and 11 thrusting against the ends of the box. The box is of a metal having a greater co-efficient of expansion than the strips 10 and 11, so that, under the influence of heat it elongates faster than the strips 10, 11, and hence permits the strips 10 and 11 to flatten.

In order to keep the box 14 from falling off the strips, suitable means is provided, here shown as lugs 15 extending inwardly from opposite ends of the box, between the ends of the strips 10 and 11. However such lugs may be dispensed with and the box held from displacement by the friction between the strips 10, 11, and the box.

In order to prevent the material of the fusible element 8 when melted from running into the passage 6 and soldering the valve

stem 5 to the web 7, a pan 16 is inserted between the fusible element 8 and the end of the valve stem 5.

In operation the fire melts the fusible element 8 in the ordinary manner, and also expands or elongates the thermostat relieving all holding effect on the valve.

Hence when the fusible element 8 is melted, the valve opens under the water pressure.

10 After the fire has been extinguished by the water and the temperature falls, the thermostat strips 10 and 11 bow away from each other and thrust against the nut 13 on the stem 5 to seat the valve head 4, and either 15 entirely or to a great extent shut off the water, so that, very little or no water damage is done after the fire has been extinguished. In case the fire is not entirely extinguished and again starts after the valve has been 20 closed by the thermostat, then the thermostat will again flatten under the heat, and permit the valve to open.

This thermostatic sprinkler head is particularly advantageous in that the thermostatic apparatus is self-contained with the sprinkler head and requires no change in the sprinkler system except the substitution of sprinklers having my thermostatic control for the standard sprinkler head.

25 30 What I claim is:

1. A thermostatic sprinkler head, comprising a body formed with a valve seat, and an attaching nipple, a valve having a head normally closing the nipple, a fusible element interposed between the body and the valve for holding the valve head against its seat, and a thermostat self-contained with the body and the valve and acting on the valve to press the valve toward its seat under low temperature conditions after the fusible element has been destroyed by fire conditions, and to permit the valve to move from its seat under fire temperature conditions.

45 50 55 2. In a thermostatic sprinkler head, a body formed with an attaching nipple, an axially movable valve having a head normally closing the nipple, and a stem guided in the body, a fusible element interposed between the body and the stem to normally hold the valve closed, and a thermostatic element mounted in the body and on the stem, and arranged to thrust against the body and the stem to hold the valve closed under low temperature conditions after the fusible element has been destroyed, and permit the valve to open under fire temperature conditions.

60 65 3. In a thermostatic sprinkler head, a body provided with an attaching nipple, and a transverse web between the ends of such body, the web being formed with a guide in line with the nipple, a valve having a head normally closing the nipple, and a stem extending through the guide, a fusible

element arranged between the end of the stem and the body, and normally holding the valve closed, the stem having a shoulder thereon, between the web and the valve head, and a thermostatic element mounted 70 on the valve stem and thrusting against the web and against said shoulder, and operating to close the valve under low temperature conditions after the fusible element has been melted, and to permit the valve to 75 again open under high temperature conditions.

4. In a thermostatic sprinkler head, comprising a body having an attaching nipple at one end, a valve having a head normally 80 closing the nipple, and a stem extending lengthwise of the body, a fusible element between the end of the stem and the body, the stem having a shoulder thereon, a thermostatic element between the body and said shoulder, and arranged to permit the valve to open by water pressure under high temperature conditions, after the fusible element is melted, and again close the valve under low temperature conditions. 85

5. In a thermostatic sprinkle head, comprising a body having an attaching nipple at one end, a valve having a head for closing the nipple and a stem extending lengthwise of the body, a fusible element between the stem and the body, the stem having a shoulder thereon, a thermostatic element between the body and said shoulder, and arranged to permit the valve to open by water pressure under high temperature conditions, after the fusible element is melted, and to again close the valve under low temperature conditions, the thermostatic element comprising bow-shaped strips, having 90 openings between their ends through which the valve stem passes, the strip being arranged to elongate and flatten under high temperature conditions, said strip thrusting at their central portions against the body 95 and the shoulder on the stem. 100

6. In a thermostatic sprinkler head, comprising a body having an attaching nipple at one end, a valve having a head normally closing the nipple, and a stem extending lengthwise of the body, a fusible element between the stem and the body, the stem having a shoulder thereon, a thermostatic element interposed between the body and said shoulder, and arranged to permit the valve to open by water pressure under high 110 temperature conditions, after the fusible element is melted, and to again close the valve under low temperature conditions, the thermostatic element comprising opposing 115 bow-shaped strips, having openings between their ends, the central portions of the strips thrusting against the body and the shoulder on the stem, and a housing enclosing the strips and against which the strips 120 thrust at their ends, the housing being of a 125 130

material having a greater coefficient of expansion than the strips.

7. In a thermostatic sprinkler head, a body formed with an attaching nipple, and a transverse web between its ends, the web being formed with a guide, a valve having a head normally closing the nipple and a stem extending through the guide and formed with a shoulder, a fusible element between the body and the end of the valve stem to normally hold the valve against its seat, thermostatic strips extending transversely of the body, the strips being bowed in opposite directions relatively to each

other, and having openings in their central portions through which the stem passes, one strip thrusting against the web and the other against the shoulder on the stem, said strips being arranged to flatten under high temperature conditions, and to bow-out-wardly and close the valve against its head under low temperature conditions.

In testimony whereof, I have hereunto signed my name, at Syracuse, in the county of Onondaga, in the State of New York, this 21st day of Jan. 1924.

ARTHUR H. TROTTER.
